UNITED STATES PATENT OFFICE.

VICTOR STOLL, OF BROOKLYN, NEW YORK.

DENTAL TOOL.

1,244,792.

Specification of Letters Patent. Patented Oct. 30, 1917.

Application filed March 7, 1917. Serial No. 153,172.

To all whom it may concern:

Be it known that I, VICTOR STOLL, a citizen of the United States of America, residing at Brooklyn, Kings county, State of New York, have invented certain new and useful Improvements in Dental Tools, of which the following is a full, clear, and exact description.

This invention relates to improvements in dental-tools or gages, the object being to simplify and improve this type of implement to such an extent that it can be more easily and accurately manipulated than those now in use.

The class of tool or gage to which my invention relates is used for the purpose of positioning missing teeth in a parallel relationship to the remaining teeth, and the tool may be provided with a paralleling device for the teeth to be set. My improvement can also be used to place in a parallel position various attachments at one operation. The invention also comprises other details of improvements and combination and arrangement of parts which will hereinafter appear.

I will now proceed to describe my invention in detail, the novel features of which I will point out in the appended claims, reference being had to the accompanying drawings, forming part hereof, wherein—

Figure 1 is a side elevation of an embodiment of my invention;

Fig. 2 is a plan view thereof;

Fig. 3 is an enlarged sectional detail view of the universally movable support for the spindle chuck;

Fig. 4 is a plan view thereof;

Fig. 5 is an enlarged sectional detail view of the upper end of the supporting post;

Fig. 6 is an enlarged face view of the testing attachment, partly in section;

Fig. 7 is a plan view thereof;

Fig. 8 is a sectional detail view, the section being taken on a line 8—8 in Fig. 7;

Fig. 9 is an enlarged plan view of the outer end of one of the arms of the testing attachment; and

Fig. 10 is an enlarged detail view of the universally movable ball which carries the chuck.

As herein embodied my dental gage comprises a base portion 11 carrying a rigid supporting post 12, to the top of which is movably secured an adjustable arm or beam 13.

To one end of the beam 13, I secure a

block 14 carrying a ball or bearing member 15 (Fig. 3) which carries a chuck 16. The ball or bearing member 15 fits in a socket 17 and is adapted to be rotated therein to cause the chuck 16 to assume various angles relative to the axis of the post 12. To secure the chuck and ball together, I employ a set-screw 18 (Fig. 4) which is carried by the ball and which also passes through a somewhat larger opening 19 in the block 14. (See Fig. 1.) The opening 19 is large enough to permit the ball 15 to be rotated to cause the chuck 16 to assume various angles. The ball, and consequently the chuck 16, is held in any desired angular position, or in a vertical position, by a set-screw 20.

To secure the beam or arm 13 in an adjusted position, I employ a set screw 21, which engages a threaded opening 22, at the bottom of a counterbore 23 in the post 12 (Fig. 5). As can be seen in Fig. 2, the arm 13 is provided with an elongated slot 24, which permits the said arm to be moved in a horizontal plane to cause the chuck 16 to be adjusted relatively to a set of teeth indicated by 25 in Fig. 1. The arm 13 can also be rotated in a horizontal plane in order that the chuck can be moved to any position desired. When properly adjusted, the arm can be locked by the set-screw 21.

In order that there will be tension upon the arm or beam 13 when the set-screw is loose, I place a spring 26 within the counterbore or socket 23 in the post 12, the spring 26 exerting, at all times, pressure upon the arm or beam 13, and when the set-screw 21 is loose, there will be enough tension to prevent the arm 13 from swinging too freely.

The chuck 16 is adapted to hold any desired type of mandrel such for instance as indicated by 27, Fig. 1, being used to set or line up the female anchor or socket which is set into a tooth to receive the male part of an inserted false tooth. When a socket has been set into one tooth, the set screw 21 will be loosened and the chuck moved to another position or to another selected tooth, after which the set-screw 21 will be fastened and the operation of setting the socket continued. When the chuck 16 is once set, any desired number of sockets can be positioned and said sockets will be in exact parallelism with each other, as it is but necessary to adjust the arm 13. The position of the chuck 16 will not be changed during the operation of adjusting the arm.

13, that is to say, its position relative to the axis of the post 12. The ball or bearing member 15 is a detachable element arranged to be removed from the block 14 in order that another bearing member or block having an opening 28 of a different diameter, can be substituted for receiving a chuck having a larger or smaller shank.

In combination with my improved gage, 10 I employ a multiple paralleling device 29, Figs. 6 and 7, consisting of a bar or carrier 30 having a slot 31 for the passage therethrough of a binding screw 32, in this instance, carried by the mandrel 33, a lock-nut 34 being employed to secure the carrier 30 in adjusted positions. The carrier 30 is curved at each end, as at 25 and 36, for a purpose presently to be described. This paralleling device is adapted to carry mandrels for tubular or square sockets.

The carrier 30 supports a plurality of arms 37 and 38 each carrying a mandrel 39 held in a triangular opening 40 by a set-screw 41. (See Fig. 9.) The arms 37 and 25 38 are adjustably secured to the carrier 30 by nuts 42 engaging threaded studs 43 passing through the slot 31. (See Fig. 8.) The arms 37 and 38 are both radially and horizontally adjustable on the carrier 30. Each 30 nut 42 is counterbored, as at 44, to receive a spring 45 (Fig. 8) for the same purpose as the spring 26 in the counterbore 23 of the fixed post 12. The nut 34 is also provided with a counterbore 46 to receive a 35 spring 47 to act as a binding element for the carrier 30 when the nut 34 is loosened. The paralleling device is used to set in parallelism at one time a number of attachments according to the form of mandrel 40 employed. It can also be used as a caliper to take measurements in the mouth, or for any desirable purpose. The curved ends 35 and 36 of the carrier act to maintain the mandrels 39 in alinement when said mandrels are adjusted to lie adjacent one another at the ends of the carrier, as shown by dotted lines in Fig. 7. As many arms 37 and 38 can be employed as may be desirable.

As can be seen in Fig. 1 the table 48 of 50 the device is rotatably supported and can also be adjusted vertically and held in adjusted positions by a set-screw 49. It will be apparent in the form of my device herein illustrated, I adjust the table vertically and not the beam 13, as it is a much easier operation and can be effected with a greater degree of accuracy, the chances of play between the parts being reduced to a minimum.

60 A further feature of my invention consists of means to set the axis of the chuck 16 in parallelism with the axis of the post 12, or in other words, to position it at a right angle to the table. To accomplish 55 this result, I provide the table with a cen-

trally located socket 50 which extends into the spindle 51 thereof. The axis of the socket 50 will be in parallelism with the axis of the table and post, and the socket will snugly fit the mandrel 27 in the chuck. 70

To set the chuck in a vertical plane the nut 21 on the post will be loosened and the beam 13 shifted to cause the mandrel to enter the socket by raising the table 75. After the mandrel has been caused to enter the socket to the full depth thereof, the set-nut 21 will be tightened, thereby locking the beam. The table will now be lowered away from the mandrel. After this operation the axis of the chuck will be in exact 80 parallelism with the axis of the post and also with the axis of the table.

What I claim as my invention is:

1. A dental-gage, consisting of a base-member, a post carried thereby, an arm adjustably secured to said post, and a ball-and-socket connection at the outer end of said arm adapted to retain a clutch, whereby the latter can be moved in circular path in a horizontal plane. 85

2. A dental-gage, consisting of a base-member, a rotatable vertically movable table carried thereby, a rigid post carried by the base-member, a slideable adjustable arm carried by said post and arranged for rotation 95 in a horizontal plane only, a chuck carried by said arm, and means to adjust said chuck to any angular position relative to the axis of the post.

3. A dental-gage consisting of a supporting member, an arm adjustably secured thereto, a block carried by said arm provided with a socket, a ball within said socket, arranged for rotation therein, a chuck carried by said ball, and means to lock said 100 ball in adjusted positions.

4. In a dental-gage, a base, a vertical post supported thereby, and a rotatable vertically adjustable table carried by said base.

5. A dental-gage, comprising a base, a 110 vertical post, an arm supported at the upper end of said post, means to secure the arm and post together, and means to exert pressure upon the arm when the securing means is loosened.

6. A dental-gage, comprising a base, a supporting post, an arm provided with an elongated slot carried by the post, the supporting post being provided with a counterbore, a spring in said counterbore bearing 120 against said arm, and a set-screw passing through the slot in the arm and securing the arm and post together.

7. A dental-gage, comprising a vertical supporting post, an arm adjustably secured 125 thereto, a block on said arm having a socket therein, a ball in said socket adapted for universal rotation therein and provided with an opening to receive a chuck, means carried by the block to lock the ball in adjusted 130

positions, and a set-screw passing through the block and into the opening in the ball and bearing against a chuck carried by the block.

5 8. A paralleling attachment for dental-gages, comprising a slotted carrier, a plurality of arms adjustably secured thereto, paralleling mandrels adjustably secured to said arms, means on the carrier to connect 10 same to a chuck, and means to exert pressure upon the arms when the securing means therefor is loosened.

9. A paralleling device for dental-jigs, comprising a carrier having a slot curved 15 for a portion of its length, a plurality of arms slidably mounted in said slot, and means for securing the arms in adjusted positions.

10. A paralleling attachment for dental-gages, comprising a slotted carrier, a plurality of arms slidably secured thereto, a tensioning spring interposed between the carrier and said securing means, to exert pressure upon each arm when the securing 25 means is loosened, a mandrel having a threaded post passing through the slot in the carrier, means for securing the mandrel to the carrier, and a spring interposed be-

tween the carrier and mandrel securing means to exert pressure upon the carrier 30 when the mandrel securing means is loosened.

11. In a dental-gage, a chuck, a vertical supporting post, a horizontally disposed arm adjustably secured to said supporting post, 35 a table adjacent said chuck, and means carried by the table to position said chuck at a right angle to said table.

12. In a dental-gage, a support, a chuck adjustably secured thereto, and means independent of the chuck support to position the axis of the chuck in a vertical plane.

13. In a dental-gage, a vertically movable table provided with a vertically disposed socket, a chuck adjustably mounted adjacent 45 said table, and a mandrel carried by the chuck arranged to snugly fit the socket in the table for the purpose set forth, the axis of said socket being in parallelism with the axis of the table.

Signed at New York city, N. Y., this 5th day of March, 1917.

VICTOR STOLL.
